PROJECTILE METHOD AND MEANS

Marion B. Robinson, Great Neck, N. Y.

Application October 7, 1947, Serial No. 778,311

3 Claims. (Cl. 102—63)

1

The present invention relates to projectiles and more particularly to one which is provided with a spring which is held in the projectile in a contracted nested coiled condition and which spring is discharged from the projectile at some point of the projectile trajectory to expand into an open spiral spring.

The present invention may be utilized as an anti-aircraft shell to provide a spring means by which the propellers of aircraft may be entangled or a large area of metal through which enemy aircraft will pass to destroy themselves upon engagement with the expanded spring.

The present invention may also be utilized in a torpedo having such a spring which may be released at the proper time to entangle the propellers of ships of all kinds and cause them to cease functioning and thus stop further propulsion of the ship.

The present invention may also be utilized with a bomb, mine, or conventional artillery shell and thus provide a spring which will be discharged therefrom and expand in open condition to present a greater area of destruction than heretofore possible.

The present invention contemplates the provision of a projectile having a spring-like metal wound therein in contracted nested condition and having means for releasing the spring whereby the spring expands to cover a large area and which releasing means may be actuated by radiant energy, such as sound, magnetism, light, heat, or radio waves, all of which have been utilized in my co-pending applications Serial No. 418,497 filed November 10, 1941, now abandoned; Serial No. 447,227 filed June 16, 1942, now abandoned; Serial No. 486,583 filed May 11, 1943, now abandoned; Serial No. 601,858 filed June 27, 1946, now abandoned; these applications being continuations of my application Serial No. 340,629 filed June 10, 1940, now abandoned; to fire an explosive or rocket charge.

It will of course be understood that the spring releasing means may be actuated by a conventional time fuse or a time fuse such as that illustrated in my co-pending applications, Serial No. 565,264 filed November 27, 1944; Serial No. 601,858 filed June 27, 1945, or Serial No. 676,373 filed June 13, 1946, now abandoned.

It will also be recognized that the projectile of the present invention may be combined with a self-directing missile such as that illustrated in my co-pending applications, Serial No. 418,497 filed November 10, 1941; Serial No. 447,227 filed June 16, 1942; Serial No. 486,583 filed May 11, 55

2

1953; which applications also are continuations of my said application Serial No. 340,629 filed June 15, 1940.

The present invention contemplates the provision of a spring wound therein in a contracted nested condition to thereby occupy a minimum space and having an explosive means for releasing the thus wound spring and which explosive means is automatically fired during the flight 10 of the projectile whereby the released spring expands into an enlarged spiral coil occupying a maximum space.

The present invention further contemplates the provision of a projectile having a coiled spring wound about an inner coil at the center of the spring and extending into a coil at the exterior of the spring, the coils being in contracted nested condition in opposition to the normal expanding tension of the spring. Means are 15 provided for normally holding the spring in nested condition and means for releasing the spring from nested condition whereby the spring is discharged from the projectile and permitted to expand as a spiral spring to cover a relatively 20 large area, the coils or convolutions of the spring having a common center and lying in a substantially common plane.

The present invention still further contemplates a projectile having a spring coiled to form 25 a plurality of connected coils, each coil having a common center and each coil lying in substantially a common plane, the center of each coil positioned along a longitudinal axis through the projectile and the outermost convolution of each 30 coil lying at the exterior of the projectile.

The present invention still further contemplates a projectile having a container for an explosive at the central interior of the projectile about which container a spring-like member is 35 wound in contracted nested condition as a spiral and which projectile has a spring retaining means dischargeable from the rear of the container by the explosive means to thereby release the spring-like member and permit it to expand 40 into normal extended spiral condition.

The present invention still further contemplates the provision of a projectile having a spring-like member wound about itself as a spiral coil and having an explosive mounted thereon, 45 preferably in the interior thereof, to thereby provide a greater area of explosion than heretofore possible.

These other and further objects and advantages of the present invention will be clear from the description which follows and the drawings

appended thereto, in the figures of which like reference characters denote like elements and in which

Fig. 1 is an elevation of a projectile according to my invention and partly in section to show the arrangement of spiral springs therein.

Fig. 2 is an elevation of a modified projectile according to my invention and in partial section to illustrate the operative elements thereof.

Fig. 3 illustrates the manner of winding the spring included in the device of Fig. 2.

Fig. 4 is an elevation of the position assumed by the spring in the device of Fig. 2 after it has been fired from the projectile.

Fig. 5 is a detailed elevation partially in section of the arming element of projectiles according to my invention.

Fig. 6 is a detail of the nose of the projectile illustrated in Fig. 2.

Fig. 7 is a schematic wiring diagram of the means for exploding the charge in the projectiles according to my invention.

Fig. 8 is a schematic wiring diagram of an antenna means for exploding the charge in the projectiles according to my invention.

Fig. 9 is a partial plan view of a modified spring according to my invention.

Fig. 10 is a partial elevation and section of a further modified projectile.

Referring now to the drawings and more particularly to Figs. 1, 5 and 7, I wind a plurality of spiral springs 10 around the container 12. As illustrated in Fig. 1, each coiled spring 10 is arranged on top of the other with the container extending through the center of each coil.

Each spring 10 may be said to be similar to a coiled watch spring, it being understood that this reference to a watch spring is solely for the purpose of illustration in understanding my invention, the spring 10 being formed from a heavy metal, such as steel, which can be coiled about itself and which will withstand the forces of explosion utilized to discharge the springs from their coiled position about the container 12, as I shall describe, and the discharge of the projectile from a gun.

The springs 10 and the container 12 are housed within the casing 14 of the projectile, the bottom wall 16 of which casing closes the open bottom of the container 12, in which container is arranged an explosive charge 18.

Preferably threadedly mounted on the casing 14, I provide the nose 20 of the projectile, in which nose a radiation responsive means 22 may be arranged. In the illustration of the drawings such radiation responsive means is shown as a photo-electric cell, responsive to heat or light, though it will be understood that an antenna may be substituted therefor that will pick-up radio waves such as illustrated in Fig. 8.

In the hollow interior 24 of the nose 20, the elements by means of which the charge 18 will be exploded, may be housed. These elements and the diagram of the wires connecting them to the explosive charge 18 are illustrated in detail in Figs. 7 and 8, to which further reference will hereinafter be made.

The nose 20 is provided with the separating wall 26 on the under side of which the arming element 28 is carried and on the upper side of which, the elements heretofore referred to are mounted.

In that one of the embodiments of my invention illustrated in Fig. 1, a plurality of springs 10

are mounted one on top of the other and coiled around the container 12 which lies at the center of the coils and the shell 14.

The springs 10 are wound about the container 12 in a tightly contracted nested condition against the inherent expanding tension of the spring and occupy a considerably smaller area across the diameter of the spring than they would when expanded into the open condition illustrated in Fig. 4, to which I shall further refer.

In Fig. 4, I have illustrated a spring 10, to which a suspending means such as the balloon 32 is secured. This is for the purpose of convenience in illustration, it being understood that the springs illustrated in the projectile of Fig. 1 are not provided with such suspending balloon. It will of course be understood that, if desired, the top spring 34 of the plurality of springs illustrated in Fig. 1 may be provided with a balloon 32, to which I shall refer in my description of the embodiment of my invention illustrated in Fig. 2 or with a single spring such as that illustrated in Fig. 3 and to which I shall refer in my description of the embodiment illustrated in Fig. 2.

It will be recognized that in this case a battery such as 68 need not be used and that the photo-electric cell 22 in such construction is replaced by the antenna 36.

It will be here noted that the convolutions 30 of the spring 10 are held against each other when the spring is in closed position in the projectile as illustrated in Fig. 1, but are spaced from each other when the spring has been released in the manner that I shall further describe to assume the open condition illustrated in Fig. 4. The distance of spacing between the convolutions of the spring are of course dependent upon the inherent tension of the material from which the spring is formed, it being understood that I desire to cover as great an area as possible, that is provide a spring of largest diameter when opened, that is consonant with the strength required for the purposes of my invention.

I shall now describe the arming element 28, illustrated in Fig. 7, by means of which my projectile is placed in condition to release the springs 10 by firing the explosive charge 18.

This arming element 28 is provided with the plunger-like member 38 which is slideably moveable in a chamber 40 from the inoperative or un-armed position to the operative or armed position against the bottom 42 of the chamber under the expansion of the spring 44.

The plunger 38 is locked in the un-armed position of Fig. 7 by the spring actuated lock pin 46, which is released by centrifugal force after acceleration has ceased, and which lock pin and plunger are conventional.

The plunger 38 at the bottom thereof is provided with the electric contact 48 mounted on the wall of the plunger.

The inside wall of the chamber 40 is provided on one side of the chamber with the electric contacts 52 and 54, which are bridged by the contact 48 when the plunger is forced to its lowermost position by the spring 44 upon release of the lock pin 46.

Thus when the projectile leaves the gun and acceleration ceases an electric circuit is completed between the battery 60 and the amplifier 62. It is unnecessary to illustrate in detail such an amplifier since it would be conventional and

have the sole purpose of amplifying the current generated by the radiation responsive means 22 sufficiently to attract the armature 64 by the solenoid 66.

As will be recognized, in order to cause a photo-electric cell to function a battery 68 is arranged between the amplifier 62 and the means 22.

The radiation responsive means 22 is recessed in the nose 88 and will receive radiant energy, either light or heat, projected from the target, such as an aeroplane, when the projectile approaches the vicinity thereof.

The current generated by the photo-electric cell 22 is amplified to attract the armature 64 and thus close a circuit between the battery 68 and the firing means 70, such as fulminate of mercury, for exploding the charge 18.

The explosion of the charge 18, which is downward in the container 12 to force the casing away from the spring 10 and upward to strip the threads 72 and blow the nose away from the casing and release the springs 10 from the container 12.

When the springs 10 are thus released, by their inherent tension they expand into the spiral condition illustrated in Fig. 4.

These expanded springs occupy a large area in the air so that they will be struck by airplanes 74 in whose path they may lie.

It will of course be understood that means may be provided in such a projectile for transmitting radiant energy, such as heat or light to the target, for example an aeroplane, which will be reflected by the target to generate current in the means 22 and release the springs 10 in the manner that I have described.

The springs 10 may be released from the projectile by radiant energy, such as conventional radio waves, sent from a remote point on the ground or elsewhere or from the projectile to be reflected by the target.

Such radio waves are picked up by the antenna 36 (see Fig. 8) and are amplified by the amplifier 62 to close a circuit between the firing means 70 and the battery 68, as I have described heretofore. The plunger 38 in Fig. 8 is shown in the projectile arming position with the contacts 52 and 54 bridged by the contact 48.

The embodiment illustrated in Fig. 2 is provided with a single spring 76, which spring comprises a plurality of coils 78, instead of a number of spirally coiled springs 10, such as illustrated in the embodiment of Fig. 1.

The single spring 76 is coiled about the container 12 in the manner which I shall now describe with particular reference to Fig. 3. The spiral coils 78 are connected to each other by the links 80 at the outermost parts of the coils and links 82 at the centers of the coils.

The single spring 76 may be wound, for example, as illustrated in Fig. 3, the center 84 of the first coil 78 being wound about the container 12 at the center of the projectile with its outermost convolution at the exterior of the shell.

This outermost convolution of the first coil is connected by the link 80 with the outermost convolution of the second coil, which is wound about itself to arrange the center 86 of the second coil about the container 12 at the center of the projectile.

The innermost convolution of the second coil is connected by the link 82 to the innermost convolution of the third coil at the center 88 thereof about the container 12, which third coil is wound about itself so that its outermost convolution is

positioned at the exterior of the projectile and continues into the link 80 to join the next succeeding coil 78 (which need not be illustrated).

This method of winding continues until a spring having the desired number of coils is provided for the projectile.

When the spring 76 is released and discharged from the projectile in the manner described with reference to the embodiment of Fig. 1 or in the manner which I shall describe, it assumes the open condition illustrated in Fig. 4. Thus with the embodiment illustrated in Fig. 4 a greater area of expanded spring can be obtained for the same size of shell. It should be here noted that with both constructions, whether a plurality of springs or a single spring, there are provided coils, each having a common center at the center of the projectile and an outermost convolution at the exterior of the projectile. The innermost convolution of each coil is wound about the container 12 at the center of the projectile and the convolutions of each coil lie in substantially the same or a common plane. When they are wound in nested contracted condition in the shell and when released therefrom the convolutions of each separate expanded coil also lie in substantially the same plane.

In the modification illustrated in Fig. 2, the nose 88 is similarly provided with a radiation responsive means 22 or an antenna 36 and the arming element 28, as well as the means for exploding the charge 18, such as illustrated in Figs. 7 and 8.

The nose 88 is provided with a compartment 90 in which the balloon or spring suspending means 32 is housed.

The nose 88 is pressed on the gas containing chamber 92 and may be separated from the gas containing chamber 92 by means of a soft metal ring 94, the function of which I shall describe.

At the center of the chamber 92, I provide a soft metal plug 96 above the puncturing element 98 on the lever 100.

The lever 100 is mounted intermediate its ends 45 to the top 102 of the chamber 92 by means of the pivot 104. Extending up from the lever 100, I provide the finger 106 which abuts against the wall 108 in the interior of the nose 88. The finger extends through an opening in the top 102 which is made air or gas tight.

The lever 100 is held in normal position, as illustrated in Fig. 6, with the finger 106 against the wall 108 by means of expanding spring 110, to dispose the puncturing element 98 away from the soft metal plug 96.

In operation, when the projectile is fired from a gun, the pressure of the wind on the nose 88 as well as the set-back arising from the acceleration of the projectile, causes the nose 88 to move 60 downwardly on the soft metal ring 94 against the chamber 92.

This movement, through the finger 106 rotates the lever 100 about its pivot 104, causing the element 98 to puncture the plug 96 in the spool 112 and the top 102.

The balloon 32 is in communication with the passage 114 in the spool, which passage is connected to the gas chamber 92. The passage 114 is closed by the plug 96 which as stated is opened 70 by the element 98. So long as the wind pressure forces the nose 88 against the chamber (which occurs until the nose 88 is blown from the projectile by the explosion of the charge 18), the puncturing element 98 keeps the passage 114 closed so that the gas contained in the chamber

92 will not be discharged therefrom into the balloon 32 to inflate it.

The upper end 116 of the spring 76 is secured to the gas chamber 92 when the spring is wound about the container 12. The lowermost convolutions 116 of the spring 76 are held in position by means of the cap 118, which closes off the open end of the container 12.

The charge 18 will be exploded by radiant energy received by the means 22 or antenna 36, as previously described, to blow off the cap 118. The resulting jar will cause the nose 88 to separate from the chamber 92 containing member, which action may be assisted by suitable spring between them, which need not be illustrated.

In order to insure that the nose 88 will be blown loose from the member 119, in which the gas chamber 92 is arranged, I connect the container 12 by means of the channel 122 to the chamber 124 on which the projection 126 rests. Thus an explosive force when the charge 18 is fired will be directed against the nose 88 to force it from the member 119 whereby the balloon 32 is inflated as I shall now describe.

Upon releasing the nose 88, the lever 100 is forced down by the spring 110 thereby opening communication through the passage 114 of the balloon 32 with the chamber 92 thereby inflating the balloon so that the spring 76, expansion of which is permitted by blowing away the cap 118, is suspended in the air in the expanded condition illustrated in Fig. 4.

In order to permit the spring to freely assume any position relative to the balloon, the spool 112 is mounted on the top 102 of the chamber 92 by means of the ball bearing 120.

It will now be recognized that the projectile 10 may be discharged from a gun located on the ground, or in an aeroplane, in a ship, in a land vehicle, in an underwater craft, etc., and the spring released by energy received by the means 22 from or reflected by a target such as an enemy aeroplane, ship, submarine or other moving vehicle or stationary target.

It will be further understood that the means 22 may be substituted by an antenna 36 so that the projectile may be exploded as heretofore described, from a remote point by sending out therefrom to the projectile radio waves of a frequency to which the antenna and the receiver amplifier 62 are tuned. Thus the springs 10 or spring 76 may be released by a person at some remote point at any selected position of travel of the projectile.

It will be further understood that a radio transmitter may be mounted in the nose of the projectile to send therefrom radio waves which are reflected by the target and received by the antenna 36, as by the means described in my co-pending application Serial No. 486,583 filed May 11, 1943; and Serial No. 557,289 filed October 5, 1944.

It will be further understood, though it need not be described in detail that the means 22 may be substituted by a conventional time fuse which may be set to explode the charge 18 and release the spring or springs at a selected time and so when the projectile has reached a desired position in its flight.

It will be further understood that the projectile described in my co-pending application Serial No. 418,497, filed November 10, 1941, which relates to directed missiles may be arranged to contain the spiral spring or springs heretofore described and the means for discharging them from the projectile. Thus, my projectile may direct

itself to a target and when in its proximity may be exploded to there release the spiral entangling springs 10 or spring 76.

The projectile illustrated in Figs. 1 and 2, is preferably provided with the rifling band 128 which imparts rotation to the projectile by the rifling grooves in the barrel of the gun from which the projectile is fired.

The spring 76 at its upper end 116 is mounted on the member 119 and at its lower end 130 to the cap 118. The connection to the member 119 is made strong enough so that the end 116 will not be disconnected from the member 119 upon the explosion of 18 but the connection of the end 130 to the cap 118 is made weak enough so that the cap 118 will be disconnected from the spring by the explosion of the charge 18.

The winding of the spring 76 is made opposite to the rotation of the projectile by the rifling band 128 so that during the flight of the projectile the spring 76 is caused to remain tightly wound about the container 12.

It will be recognized that the force of the explosion of the charge 18 is arranged so that it will be directed downwardly in the container 12 to force the casing 14 away from the springs 10. In order to insure scattering of the springs 10 upon their release from the casing 14, I arrange the explosive charge 132 along the bottom wall 16.

In order to explode the charge 132, I connect it to the container 12 by means of the channels 134. Thus when the charge 18 is exploded, the charge 132 is concurrently fired to force the springs 10 outwardly of the casing 14 as the nose 20 is released from the casing as heretofore described. It will be recognized that the casing 14 functions similarly to the barrel of a rifle to discharge the spring therefrom by the explosion of the charge 132.

The interior of the casing 14 may be rifled by grooving it so that the springs 10 when they are fired from the casing by the explosion of the charge 132, they will have imparted to them a spin or rotation similar to that of a shell fired from a gun.

The spiral springs 10 or the single spring 76 may have preferably in the interior thereof a charge which will be exploded upon contact of the spring by any object which it engages. It will be recognized that the spiral spring or springs may be mounted in a bomb from which the spring will be released at a selected time after the bomb is discharged or a wound spring, containing the explosive charge, either in the interior or on the exterior of the spring, may be released from a plane, for example, and thus itself constitute the bomb.

In any event, by thus arranging in or on the spring an explosive charge, there is provided an extremely large explosive area not heretofore realized since the expanding spring will occupy a large space and thus distribute the explosive charge throughout the area in which the expanded spring is located.

Referring now to Fig. 9, I have there illustrated in a fragmentary view of a modified form of spiral spring, particularly that illustrated in Fig. 2, which constitutes a spring-like bomb 136. This modified form of spring at its lower end is wound around a fuse 138 which may be a conventional time fuse or proximity fuse, which therefore need not be described in further detail.

The spring and the fuse around which is wound in a tightly nested contracted condition constitute a bomb which may be dropped from an aero-

plane. Upon release of such a bomb-like spring, the inherent expanding tension of the spring will cause it to expand into the spiral condition illustrated in Fig. 9, with the fuse 138 at the center of the spiral.

The interior of the spring is arranged to carry an explosive charge, which may alternatively be arranged on the outside of the coils. As the spring approaches the proximity of the target, the fuse 138 (if it is a proximity fuse) will explode the charge carried by the spring. It will be recognized that the spring, since it has expanded into an enlarged spiral, covers a large area of size not heretofore possible of accomplishment, over which area the charge will be exploded.

This unusually large area throughout which the explosion occurs can also be effected by using a conventional time fuse at the center of the spring which fuse will explode the charge after the lapse of a selected time period, determined upon release of the spring bomb from a plane.

It will be further understood that the spring bomb illustrated in Fig. 9 may have mounted on its other end a suspending means such as the balloon 32 (Fig. 4), parachute or other such means. Thus the spring bomb may be held suspended in the air after it has been released and expanded into the enlarged spiral form. Thus a spring of this kind may be dispersed throughout a selected space and will be exploded either by contact or by the effect of the approach of the target on a proximity fuse mounted on the spring bomb.

It will be further understood that there may be substituted for the use 138, a radio wave receiving device and combined exploding means such as that illustrated in Fig. 8. Where such construction is used, the springlike bomb 136 may be exploded by sending to it from a remote point, either in an airplane or on the ground, radiant energy from a transmitter. Upon the receipt by the antenna 36 (arranged in the springlike bomb 136), the explosive charge carried by the expanded spiral spring will be fired, as desired.

Referring now to Fig. 10, I have there illustrated a further modified form of spiral spring, such as that illustrated in Fig. 2, and having a form of time fuse. The lower coils 140 of this spring are provided with a relatively slow burning charge and the remainder of the coils carry therein and thereon or either an explosive charge.

With such construction the cap 118 is provided with the groove 142 which communicates at one end with the interior of the container 12 and the other end with the slow burning charge on or in the coils 140.

In operation, upon explosion of the charge 18, the cap 118 will be blown off and the spring 76 released. Concurrently the explosion will start the charge on or in the coils 140 to burn. By the proper selection of the type of powder, the time of burning thereof can be selected and so the time when the explosive charge in the remainder of the coils is fired. This of course is selected to occur at such time when the spring 76 will have completely expanded.

It will be understood that the walls of the container 12 are chosen of such strength that they will withstand the force of explosion of the charge 18 to insure that it will be directed downward to force away the casing 14 or the cap 118 and upwardly to dismount the nose 20 or the nose 88 as heretofore described. Further the charge 18 is likewise chosen of such explosive characteristic that this will be accomplished without damage to

the spring or any other elements or members mounted thereon.

The explosive charge carried by the springs 10, spring 76 or springlike bomb 136 may if desired be substituted by a material that gives off a light, for example a phosphorus, so that the springs or spring become flares. By reason of the unusually large area covered by the expanded spiral spring there will thus be provided a flare by means of which an extremely large area will be lighted.

It will be understood that the various elements of my device that are responsive to radiation may be protected against damage from set-back occurring when the projectile is fired from a gun or is accelerated by a means such as that illustrated in my co-pending application Serial No. 418,497 filed November 10, 1941; and Serial No. 554,814 filed September 19, 1944, now Patent No. 2,614,814, in which the set-back is absorbed by a liquid bearing means.

It will be understood that any or all parts of my earlier inventions previously mentioned, may be used with any or all parts of this invention, such as the projection of the springs 10 or the spring 76, or the spring 136, from the multi-bore projectile of Serial No. 601,858 filed June 27, 1945; or Serial No. 676,373 filed June 13, 1946 or the multi-bore gun of Serial No. 565,264 filed November 27, 1944.

This spring may also be in the form of a rocket by adding a conventional rocket chamber at its rear end 16 or 118 or at the rear end of the spring 136, and be projected by the rocket force contained in the chamber.

While I have described in detail embodiments of my invention, these are for purposes of illustration and I do not intend to be limited to the details shown and described.

Hence I intend to be limited only by the claims appended hereto and the state of the prior art.

I claim:

1. A missile, comprising a nose member including a container for gas and a hollow windshield releasably mounted on the container; a collapsed balloon within the windshield; conduit means connecting the balloon and the gas container; a cap member spaced from the nose member; an elongated hollow supporting member extending between the nose member and the cap member; a series of spiral springs wound about the supporting member in contracted juxtaposition, the springs being connected together and being fastened at one end to the gas container; means within the hollow supporting member for separating the cap member and the nose member and for ejecting the windshield from the gas container; and valve means for releasing the gas from the container into the balloon upon the separation of the windshield from the container.

2. A missile, comprising a nose member including a container for gas and a hollow windshield releasably mounted on the container; a collapsed balloon within the windshield; conduit means connecting the balloon and the gas container; a cap member spaced from the nose member; an elongated hollow supporting member extending between the nose member and the cap member; a series of spiral springs wound about the supporting member in contracted juxtaposition, the springs being connected together and being fastened at one end to the gas container; means within the hollow supporting member for separating the cap member and the nose member and for ejecting the windshield from

the gas container; a diaphragm closing the conduit means; and means for puncturing the diaphragm during the flight of the missile and for releasing the gas from the container into the balloon upon the separation of the windshield from the container. 5

3. A missile, comprising a nose member including a container for gas and a hollow windshield frictionally mounted on it and having limited rearward movement relative thereto, a collapsed balloon within the windshield; conduit means connecting the balloon and the gas container; a diaphragm closing the conduit means; a cap member spaced from the nose member; an elongated hollow supporting member extending between the nose member and the cap member; a series of spiral springs wound about the supporting member in contracted juxtaposition, the springs being connected together and being fastened to the gas container; means within the hollow supporting member for separating the cap member and the nose member and for ejecting the windshield from the gas container; and means for puncturing the diaphragm when the windshield moves rearwardly relative to the gas 25

container and for releasing the gas from the container into the balloon upon the separation of the windshield from the gas container.
